UNITED STATES PATENT OFFICE

WILLIAM A. NESTER, OF EAST ST. LOUIS, ILLINOIS, ASSIGNOR TO OBEAR NESTER
GLASS COMPANY, OF ST. LOUIS, MISSOURI, A CORPORATION OF MISSOURI

DESIGN FOR A BOTTLE

Application filed February 15, 1933. Serial No. 47,221. Term of patent 14 years.

To all whom it may concern:

Be it known that I, WILLIAM A. NESTER, a citizen of the United States, residing at East St. Louis, county of St. Clair, Illinois, have invented a new, original, and ornamental Design for a Bottle, substantially as shown in the accompanying drawing, in which—

Fig. 1 is a perspective view of a bottle embodying my new design.

Fig. 2 is a side elevation.

Fig. 3 is a plan view.

I claim:

The ornamental design for a bottle substantially as shown.

WILLIAM A. NESTER.
